MANUFACTURE OF FABRICS

Filed Oct. 28, 1930

UNITED STATES PATENT OFFICE

JAMES MORTON, OF CRAMOND BRIDGE, WEST LOTHIAN, SCOTLAND

MANUFACTURE OF FABRICS

Application filed October 28, 1930, Serial No. 491,745, and in Great Britain November 21, 1929.

This invention relates to a method of and means for supplying lengths of yarn and the like (such as lengths of thread or even of knitted or cut lengths of chenille, and hereinafter referred to simply as "yarn") in parallel formation for incorporation into fabrics while being manufactured.

The object of the invention is to provide an improved method and means as aforesaid, whereby it will be possible to supply the requisite lengths of yarns more speedily, cheaply and conveniently than was possible heretofore.

According to the invention, the improved method consists in initially binding the lengths of yarn in parallel formation by means of parallel chains of loops formed from yarn by use of knitting or sewing needles and moving the looped yarn chains in unison past means for engaging said lengths, and withdrawing them in succession from said chains so that they can be incorporated in the fabric being produced. The lengths of yarn pass through equi-spaced loops of the chains the whole taking the form of a ladder, the sides of which are represented by the chains and the rungs of which are represented by the lengths of yarn.

Where the lengths of yarn conveyed by the chains have to be short, i. e. when required for incorporation as pile tufts in tufted fabrics, comparatively great lengths of yarn are bound by means of pairs of parallel looped yarn chains so as to form a preparatory fabric, then these lengths are cut between said pairs of chains so as to divide the fabric into narrow "ladders," and the ladders are each moved past means for engaging the short cut lengths or tufts and withdrawing them in succession from the respective pairs of chains.

The means for moving, or feeding, the ladder to the engaging and withdrawing means above mentioned preferably comprises two spaced feed-wheels the peripheries of which are grooved to receive the chains and notched or toothed to provide recesses for engaging with the lengths of yarn. The notches are pitched so that they register precisely with the lengths of yarn, and guide

means are provided to lead the ladder properly to the wheels.

In order that the invention can be clearly understood, reference will now be made to the accompanying diagrammatic drawings, 55 in which:—

Fig. 1 is an elevation of means for feeding the ladder to gripping means.

Fig. 2 is an elevation at right angles to Fig. 1. 60

Fig. 3 is a perspective view of sewing mechanism for producing the chains as part of a preparatory fabric.

Fig. 4 is a view of a piece of preparatory fabric such as could be produced by the sewing mechanism hereinafter described with reference to Fig. 3. 65

Referring to Figs. 1 and 2, the parts therein shown comprise a pair of feed-wheels 5, a shaft 6 on which the wheels are mounted 70 and a pair of fixed ploughs of which only one is shown, being denoted by 7. Each wheel 5 comprises two peripheral flanges which are spaced apart to form an annular groove 8 and which are notched to provide 75 recesses 9. The ploughs 7 have concave faces 10 which enter the annular grooves 8 in the respective wheels 5.

The feed-wheels are associated with a pair of grippers each comprising an arcuate arm 80 11 and a hooked finger 12, fitting through the arm and movable relatively thereto in such a manner that it can be brought resiliently against the free end thereof, and thereby seize a length of yarn supplied to it. 85

The grippers can be of the kind described in the co-pending patent specification filed of even date herewith in which specification grippers are described as incorporated in a gripper loom for the purpose of introducing tufts to, and knotting them in, the fabrics woven by the loom.

In that event, there would be as many feed-wheels as grippers, and the shaft 6 would be arranged parallel to the gripper-carrying shaft. Further, the feed-wheels would be arranged to travel across the loom at the rear of the grippers, in unison therewith, as the grippers were moved across the fabric to introduce and bind the tufts successively and side-by-side 100

into the fabric, so that the feed-wheels would always maintain the same relationship to the grippers.

The tufts, which consist of short lengths 5 L of yarn, are shown bound to looped yarn chains C which are led around the grooves 8 in such a manner that the tufts register with the recesses 9, accurate registration being ensured by the ploughs 7, the surfaces 10 of which guide and press the tufts into the recesses.

In the operation of the means above described, the shaft 6 and feed-wheels 5 thereon are rotated intermittently, so as to bring 18 the lengths L one at a time into a position in which they can be seized and withdrawn by the grippers.

The ladder constituted by the chains C and lengths L must be formed with great 20 accuracy, and to this end the chains can be knitted or sewn by means of needles such as described in my concurrent patent specification numbered 490,281 the lengths being supplied to the needles in any suitable manner.

Where ladders have to be formed the rungs of which are represented by short lengths or tufts intended for ultimate incorporation as pile in fabrics such as oriental carpets, a large number of parallel chains 30 may be initially knitted or sewn to bind together comparatively great lengths of yarn into the form of a broad preparatory fabric. Sewing mechanism such as described in 35 my aforesaid specification numbered 490,281 can be readily adapted so as to produce the requisite preparatory fabric. For example, as shown in Fig. 3, the sewing needles 20 are arranged in pairs, and looper points 21, 40 with which the needles co-operate are likewise arranged, the needles or points constituting each pair being spaced more widely apart than adjacent pairs. The numeral 22 denotes an intermediate retaining member 45 down one side of which the fabric passes to a rotating take-up beam (not shown).

The particular manner in which the sewing mechanism operates to produce the fabric forms no part of this invention and is therefore not described herein.

Fig. 4 illustrates a fragment of the preparatory fabric which would be produced by sewing mechanism arranged as illustrated in Fig. 3 and operating as described in my aforesaid specification No. 490,281. As shown, the fabric consists of pairs of chains C which bind together lengths L of yarn extending from pair to pair of chains throughout the width of the fabric, the chains constituting each pair being more widely spaced apart than adjacent pairs. After the fabric is produced (or while it is being produced), it is made into ladders by cutting along the lines A—A between the 60 respective pairs of chains, and these ladders

can be supplied as hereinbefore described to a pair of feed-wheels, such as 5, 5 and associated parts.

As will be manifest, by employing the method and means hereinbefore described, it will be possible to bind the lengths of 70 yarn in parallel formation with great rapidity and cheaply. Moreover, the lengths are held firmly in place during conveyance, but are held in such a manner that they can be 75 withdrawn easily from the chains.

It is to be understood that the means hereinbefore described have been chosen merely by way of example, and that modifications can be made without departing from 80 the scope of the invention.

I claim:—

1. A method of supplying, to a given position, lengths of yarn for incorporation in fabrics during the manufacture thereof, 85 which consists in forming yarns into side-by-side chains of loops, chaining together in parallel formation successive lengths of the yarn to be supplied by introducing them into appropriately spaced loops, and moving 90 said chains past said position to permit said lengths of yarn to be withdrawn in succession.

2. A method of supplying, to a given position, lengths of yarn for incorporation in fabrics during the manufacture thereof, 95 which consists in forming yarns into two side-by-side chains of loops, chaining together in parallel formation successive lengths of the yarn to be supplied by introducing them near their ends into appropriately spaced loops, and moving both of 100 said chains in unison past said position to permit said lengths of pile yarn to be withdrawn in succession from between said chains.

3. A method of supplying, to a given position, lengths of yarn for incorporation in fabrics during the manufacture thereof, 105 which consists in forming yarns into side-by-side chains of loops, chaining together in parallel formation successive lengths of the yarn to be supplied by introducing them into appropriately spaced loops, thereby forming a preparatory fabric, cutting said lengths between selected chains so as to divide the fabric into narrow strips, and moving the chains of each strip in unison past said position to permit the cut lengths of 110 yarn to be withdrawn in succession.

4. A method of supplying to the grippers of a gripper loom tufts of pile yarn for incorporation in fabrics during their manufacture on said loom, which consists in forming yarns into pairs of parallel chains of loops, chaining together in parallel formation successive lengths of pile yarn by introducing them into appropriately spaced loops, thereby forming a preparatory fabric, cutting said lengths between selected chains 115 120 125 130

so as to divide the fabric into ladders, each ladder being composed of two side chains and transverse tufts of pile yarn, and moving the chains of each ladder in unison past 5 said grippers to permit said tufts to be withdrawn in succession thereby.

5. A device for supplying to a given position lengths of yarn conveyed by looped yarn chains for incorporation in fabrics 10 during the manufacture thereof, said device comprising spaced feed members, tracks on said members to receive said chains, recesses on said members to receive said lengths, and means for moving said feed members so as 15 to move said chains past the given position.

6. A device for supplying to a given position lengths of yarn conveyed by looped yarn chains for incorporation in fabrics during the manufacture thereof, said device 20 comprising spaced feed wheels, annular tracks on said wheels to receive said chains, flanges on said wheels adjacent said tracks, equi-spaced recesses on said flanges to receive said lengths, and means for rotating 25 said feed wheels so as to move said chains past the given position.

7. A device for supplying to grippers of a gripper loom tufts of pile yarn conveyed by a pair of looped yarn chains for incorporation in fabrics during weaving thereof 30 on said loom, said device comprising a pair of spaced feed wheels, annular tracks on said wheels to receive said chains, flanges on said wheels adjacent said tracks, equi- 35 spaced recesses on said flanges to receive said tufts, and means for rotating both said feed wheels in unison so as to move said pair of chains past the said grippers to enable the tufts to be withdrawn thereby from 40 between the chains.

8. A device for supplying to a given position lengths of yarn conveyed by looped yarn chains for incorporation in fabrics during the manufacture thereof, said device 45 comprising spaced feed members, tracks on said members to receive said chains, recesses on said members to receive said lengths, guide means adapted to lead the chains properly on said tracks with the 50 lengths of yarn in register with the recesses, and means for moving said feed members so as to move said chains past the given position.

9. A device for supplying to a given position lengths of yarn conveyed by looped yarn chains for incorporation in fabrics during the manufacture thereof, said device comprising spaced feed wheels, annular tracks on said wheels to receive said chains, 60 flanges on said wheels adjacent said tracks, equi-spaced recesses on said flanges to receive said lengths, guide means adapted to lead the chains properly on said tracks with the lengths of yarn in register with the 65 recesses, and means for rotating said feed

wheels so as to move said chains past the given position.

10. A device for supplying to grippers of a gripper loom tufts of pile yarn conveyed by a pair of looped yarn chains for incorporation in fabrics during weaving thereof 70 on said loom, said device comprising a pair of spaced feed wheels, annular tracks on said wheels to receive said chains, flanges on said wheels adjacent said tracks, equi-spaced recesses on said flanges to receive said tufts, a pair of guide members to lead the chains properly on said tracks with the tufts of pile yarn in register with the recesses, and means for rotating both said feed wheels in 75 unison so as to move said pair of chains past the said grippers to enable the tufts to be withdrawn thereby from between the chains.

In testimony whereof I affix my signature.

JAMES MORTON.
